UNITED STATES PATENT OFFICE.

FOSTER J. BORDEAUX, OF BOSTON, MASSACHUSETTS, ASSIGNOR TO AUTOMATIC APPLIANCE COMPANY, OF BOSTON, MASSACHUSETTS, A CORPORATION OF MASSACHUSETTS.

COUPLING.

1,174,473.

Specification of Letters Patent. Patented Mar. 7, 1916.

Application filed April 23, 1915. Serial No. 23,497.

To all whom it may concern:

Be it known that I, FOSTER J. BORDEAUX, a citizen of the United States, and resident of Boston, in the county of Suffolk and State 5 of Massachusetts, have invented new and useful Improvements in Couplings, of which the following is a specification.

This invention relates to couplings, and more particularly to a coupling for an air 10 pump and the valves of pneumatic tires.

Its object is to provide a coupling for this purpose which can be quickly and easily placed in position over the valve stock and valve of the tire, and when in operative position effectively prevents leakage of the air. 15

Referring to the drawings which illustrate an embodiment of my invention, Figure 1 is a side elevation of my improved coupling; Fig. 2 is a bottom view thereof; Fig. 20 3 is a section on the line 3—3, Fig. 1; Fig. 4 is a section on the line 4—4, Fig. 2; Fig. 5 is a sectional view on a plane at right angles to Fig. 4; Fig. 6 is a section on the line 6—6, Fig. 1; Fig. 7 is a perspective view 25 of one of the shell members; Fig. 8 is a rear elevation of the coupling with the pipe removed; Fig. 9 is a perspective view of another of the shell members; and Fig. 10 is a perspective view of the head.

30 The casing or shell of the coupling consists of the two members A and B, rigidly fastened together and preferably cylindrical as shown. The outer or cap member A has a skirt A' extending part way around 35 its periphery and provided with a pair of flaring arms A². Preferably, as shown, said skirt and arms are formed by slitting the metal and bending it back, thus forming an opening A³ through the side of the member A.

40 The inner shell member B which is open at both ends, has an aperture or slot B' in its side wall, and a vertical slot B² connecting therewith. At its bottom is a holding flange B³, and screw holes b are provided which register with the screw holes a of the cap member A when the shell members are assembled.

45 C is the head of smaller diameter than the shell member B, provided on its top with a cam D, and having a laterally extending connecting nipple E adapted to be inserted into the tubing K which in turn is connected

to an air pump. Within said shell member B and between said flange B³ and the end 55 or mouth of head C, is a ring or sleeve F of rubber or similar compressible material.

In assembling the coupling, the compressible ring F is first placed within the shell member B resting on the holding flange 60 B³. The head C is then inserted into said shell member B, the neck or nipple E passing through the vertical slot B² into the aperture or slot B' and projecting therefrom. The cap member A is then placed over the 65 member B and the screw S passed through said holes a and b, thus securing the parts together. The length of the head C is such that when it is secured within the shell as above described, its lower edge is in engagement with the ring F, and the cam D at its top engages the screw S so that said screw serves the double function of a fastening for the telescoping shell members and a cam follower. When the cam follower S rests on 75 the lowermost parts of the cam surfaces D the compressible sleeve F is in extended or normal position, as shown in Fig. 4.

In use, the coupling having been placed over the valve stock of the tire, the user 80 grasps the arms A² with thumb and finger and rotates the shell to the right. This rotary movement causes the cam follower S to ride upward upon the cams D, thus forcing the head C and lip B³ toward each other and 85 compressing the ring F as shown in Fig. 5, so that it will bulge or swell and makes intimate contact with the valve stock of the tire forming a tight seal therewith and preventing leakage of the air. 90

95 My improved coupling is of simple construction, can be readily and economically manufactured, and furnishes efficient means for preventing leakage of the air between the pump and the tire valve. The valve stock to which the coupling is applied, is usually screw threaded, and the slight rotation of the shell in applying the coupling not only compresses sleeve F about said threaded valve stock but also tends to screw 100 the compressed sleeve F downward a little upon the valve stock, thus still further insuring a tight seal between the sleeve F and the valve stock.

I claim:

105 A coupling comprising a shell of two tele-

scoping members, one of said members having a skirt and laterally extending arms and the other having a slot and a holding flange, a head within said shell having a cam and a 5 connecting member projecting from said slot, a compressible member between said head and said holding flange, and said shell having a cam follower whereby rotation of

said shell compresses said member between said head and said flange. 10

Signed by me at Boston, Massachusetts, this 21st day of April, 1915.

FOSTER J. BORDEAUX.
